UNITED STATES PATENT OFFICE.

NICHOLAS R. MURPHY, OF NEW YORK, N. Y.

BED-BOTTOM.

SPECIFICATION forming part of Letters Patent No. 770,090, dated September 13, 1904.

Application filed May 6, 1904. Serial No. 206,736. (No model.)

To all whom it may concern:

Be it known that I, NICHOLAS R. MURPHY, a citizen of the United States, residing at New York, in the county of New York and State 5 of New York, have invented new and useful Improvements in Bed-Bottoms, of which the following is a specification.

My invention pertains to bed-bottoms, more particularly bed-bottoms of fabric and spring 10 supports; and it has for its object to provide a bed-bottom having a resilient fabric support which is calculated to prevent undue sagging of the fabric, especially the center thereof, and at the same time lend strength 15 and durability to the fabric without lessening the resiliency of the bottom, but rather increasing the same.

With the foregoing in mind the invention will be fully understood from the following 20 description and claims, when taken in connection with the accompanying drawings, forming part of this specification, in which—

Figure 1 is an inverted plan view of the bed-bottom constituting the present and preferred embodiment of my invention with the 25 major portion of the fabric broken away, and Fig. 2 is a detail transverse section taken in the plane indicated by the line 2 2 of Fig. 1 looking in the direction of the arrow.

Similar letters of reference designate corresponding parts in both views of the drawings.

The frame of my novel bed-bottom may be of any construction compatible with the purposes of my invention; but I prefer to have 35 it comprise side bars A and end bars B, fixed with respect to the side bars and disposed in a horizontal plane above the intermediate portions of said side bars. The fabric C, which is interposed between and connected to the 40 end bars B of the frame in the usual manner, is preferably a woven-wire fabric of one or more thicknesses, although any other fabric suitable to the purposes of my invention may be employed without involving a departure 45 from the scope of the invention.

The fabric support D, in which my invention chiefly resides, is made up of the following instrumentalities, viz: an open preferably circular body a, of wrought-iron or other 50 suitable material, which is preferably flat in

cross-section and is disposed below the central portion of the fabric C, as shown in Fig. 2; crossed rods b, preferably of wire, disposed within the open body a; coiled springs c, which are interposed between and connected to the 55 ends of the said rods b and the body a; rods d, preferably of wire, connected at their outer ends to the end bars B of the frame at intermediate points in the length of said end bars, and coiled springs e, interposed between and 60 connecting the inner ends of the rods d and the central open body a. The springs c and e are preferably expanded or under tension and are by preference of such size in cross-section as to extend above the upper side of 65 the body a, as shown in Fig. 2. In virtue of this construction it will be observed that while the body a affords a strong and durable support for the plurality of springs the 70 springs alone contact with the fabric, and hence the fabric, particularly the central portion thereof, is supported and held against undue sagging in an efficient manner and without robbing the bottom of the desirable 75 resiliency. On the other hand, it will be noticed that the several springs contribute very materially in rendering the bottom as a 80 whole highly resilient. It will further be observed that the body a, supported by the rods d and the springs e, and the rods b and springs 85 c, arranged in and supported by the said body a, lend strength and durability to the center of the fabric and render the bottom easy and comfortable at all points.

It will be appreciated from the foregoing 85 that with all of its practical advantages my novel bed-bottom is as simple and inexpensive as the ordinary bed-bottoms extant.

I have entered into a detailed description of the construction and relative arrangement of 90 the parts embraced in the present and preferred embodiment of my invention in order to impart a full, clear, and exact understanding of the said embodiment. I do not desire, however, to be understood as confining my 95 self to such specific construction and relative arrangement of parts, as such changes or modifications may be made in practice as fairly fall within the scope of my invention as claimed.

Having described my invention, what I 100

claim, and desire to secure by Letters Patent, is—

1. In a bed-bottom, the combination of a frame, fabric connected thereto, and a support for the fabric comprising an open body, rods connected at their outer ends to opposite bars of the frame, coiled springs interposed between and connecting the inner ends of said rods and the body, crossed rods arranged with 10 in the open body, and coiled springs interposed between and connected to the open body and the ends of the said crossed rods.
2. In a bed-bottom, the combination of a frame, fabric connected thereto, and a support for the fabric comprising an open body which is flat in cross-section, rods connected at their outer ends to opposite bars of the frame, coiled springs interposed between the inner ends of said rods and the open body and resting 15 above the upper side of the body so as to hold the fabric off the same, crossed rods disposed within the body, and coiled springs interposed between and connecting the body and the ends of the crossed rods and resting above 20 the upper side of the body so as to assist in holding the fabric off the same.

3. In a bed-bottom, the combination of a frame, fabric connected thereto, and a support for the fabric comprising an open body, coiled springs connected with said body and opposite 30 bars of the frame and extending above the upper side of the body so as to hold the fabric off the same, and one or more coiled springs arranged within and connected with the open body and extending above the upper side of 35 said body so as to assist in holding the fabric off the same.

4. In a bed-bottom, the combination of a frame, fabric connected thereto, and a support for the fabric comprising an open body, connections between said body and the frame, crossed rods arranged within the open body, and coiled springs interposed between and connected to the open body and the ends of the 40 said crossed rods.

In testimony whereof I have hereunto set my hand in presence of two subscribing witnesses.

NICHOLAS R. MURPHY.
